UNITED STATES PATENT OFFICE.

FRANCIS X. MALOCSSAY, OF NEW YORK, N. Y., ASSIGNOR TO INTERNATIONAL BANDING MACHINE COMPANY, OF NEW YORK, N. Y., A CORPORATION OF NEW YORK.

CIGAR-PACKING DEVICE.

1,403,047.

Specification of Letters Patent. Patented Jan. 10, 1922.

Application filed September 15, 1920. Serial No. 410,435.

To all whom it may concern:

Be it known that I, FRANCIS X. MALOCSSAY, a citizen of the United States, and resident of the city of New York, county of Westchester, and State of New York, have invented certain new and useful Improvements in Cigar-Packaging Devices, of which the following is a specification.

The object of this invention is to provide

10 a device by means of which cigars or articles of similar character may be easily handled and packed in boxes. My invention is particularly applicable as an attachment to cigar banding machines enabling unbanded 15 cigars to be removed from a box and after the same have been banded, to be easily returned to the box again.

With these object and other objects which may hereinafter appear in view, I have devised the particular arrangement of parts 20 hereinafter set forth and more particularly pointed out in the claims appended hereto.

Reference is to be had to the accompanying drawings forming a part hereof in 25 which—

Figure 1 is a plan view of my improved cigar packing device;

Figure 2 is a front elevation of the same;

Figure 3 is a sectional view on the line 30 3—3 of Figure 1 looking in the direction of the arrows;

Figure 4 is a transverse sectional view of my improved cigar packing device;

Figure 5 is a front elevation, partly in 35 section, of the cigar support showing the manner in which the cigars are removed therefrom and carried to the cigar box in which they are to be packed;

Figure 6 is a transverse sectional view of 40 the movable cigar support and surrounding parts;

Figure 7 is a view of the underside of the friction device for holding the cigar support in any desired position and

45 Figure 8 is a sectional view on the line 8—8 of Figure 7 looking in the direction of the arrows.

Throughout the various views of the drawings, similar reference characters designate similar parts.

In the preferred embodiment of my invention as disclosed in the accompanying drawing, 1 indicates a table which is adapted to support the banded cigars. This table 55 may, if desired, form a part or an extension

of a portion of the cigar banding machine from which the banded cigars are ejected.

Secured upon the upper face of the table 1 is a plate 2 which is provided with a lateral extension or flap 3 which projects outside of the table 1 and is preferably inclined at an angle to enable cigars to be slid rapidly from the table and on to the movable cigar support hereinafter described.

Secured to the underside of the table 1 is 65 a pair of spaced-apart supporting brackets 4. At 5 is a supporting member provided with end plates 6 which terminate at their upper ends in ears 7 which are pivoted to the brackets 4 by means of pins 8.

The support 5 may be held in an inclined position if desired, by means of a rod 28 which is pivotally attached to a bracket 29 secured to the support 5. The rod is provided near its outer end with notches 30 75 which engage a pin 31 in a bracket 32 secured on the underside of the table 1.

At 9 is a shelf which is movable with respect to the supporting member 5 and is provided with a strip 10 which enters into 80 and moves in a slot 11 in the supporting member 5. The shelf 9 may be fixed in any position by means of the bolt 12 provided at its inner end with an enlarged head 13 and on its outer end is threaded a wing nut 14. 85 By means of this bolt 12 the shelf can be fixed in any desired position on its support 5. At 15 is a tubular guide which extends downwardly from the under side of the shelf 9 and is provided with a lug 16 90 secured to a part of the shelf 9. Movable in the tubular guide 15 is a rod 17 and fixed to the upper end of said rod is the cigar support 18 on which the cigars are adapted to be received from the table 1. 95

The cigar support 18 is provided with an inclined upper surface 19 and a groove 20 in which rests the cigar-removing ribbon or tape 21. The cigar support 18 is provided with an end plate 22 and side plates 23. 100 Fixed at the sides of the cigar support 18 are guides 24 between which the cigar support is raised and lowered. It will be understood from the foregoing that the cigar support is vertically movable and when it is 105 desired to remove cigars from the table onto the support 18, this support is moved until its inclined upper face 19 rests on a line with the angle of inclination of the flap or extension 3 on the plate 2. The first layer 110

of cigars 25 may be rapidly swept from the table 1 on to the cigar support 18 and the cigar support is then lowered by slight pressure to receive a second layer of cigars on top of the first mentioned layer and this procedure is continued until as many layers of cigars have been received on the support as the box in which they are to be packed can accommodate.

10 The rod 17 which depends from the cigar support 18 is movable in its tubular guide 15 against frictional resistance which is produced by a suitable friction-clamp comprising a fixed block 26 and a movable spring-pressed block 27.

15 After the desired amount of cigars have been received on the support 18, they are removed therefrom by means of the ribbon 21 which normally lies in the groove 20. The 20 manner in which the same may be removed is disclosed in Figure 5 wherein it will be seen that the ribbon embraces the cigars and holds the same in position to be immediately deposited in a box, indicated at 28, which is 25 ready to receive them. The box 28 is supported upon a suitable shelf 29 resting upon the shelf 9. The box is clamped in position on said shelf 29 by means of a movable spring-pressed clamping member 30 which 30 forces the box against abutments 31 fixed upon the shelf 29. The abutments 31 and the spring-pressed clamping member 30 are each provided with prongs 32 which firmly grip the sides of the box and hold the same 35 to prevent it from shifting while cigars are being removed therefrom or placed therein. The spring-pressed clamping member 30 is disclosed in detail in Figure 3 wherein it will be seen that the same comprises a rod 33 on one end of which is the head 34. The spring 35 abuts against a shoulder 36 on said rod. The spring is enclosed in a casing 36.

40 From the foregoing the operation of my improved cigar packing device will be 45 readily understood. A box of unbanded cigars is placed upon the shelf 29 between the gripping members 30 and 31. The cigars are removed therefrom and fed to the band-

50 ing machine. The banded cigars are ejected from the machine onto the table 1. From there, they are slid onto the cigar-receiving support 18 in the manner heretofore described. When all of the cigars that are intended to be received in the box are placed 55 upon the support 18, they are removed therefrom by means of the ribbon 21 and deposited in the box and the ribbon removed therefrom and placed in its groove 20 to receive the next batch of cigars.

60 From the foregoing it is obvious that my invention is not to be restricted to the exact embodiment shown but is broad enough to cover all structures coming within the scope of the annexed claims.

65 What I claim is:—

1. A device of the class described comprising a table, a support vertically movable adjacent said table and adapted to receive cigars therefrom, guides at the sides of said support, said support having an inclined upper face and a ribbon groove in said face.

2. A device of the class described comprising a table, an inclined flap thereon, a cigar receiving support having a downwardly extending rod, a guide in which said rod is movable and means for frictionally resisting movement of said support.

3. A device of the class described comprising a table, a movable support adapted to receive successive layers of cigars that are slid off of said table and a ribbon groove in said support adapted to receive a ribbon for removing the cigars from said support.

4. A device of the class described comprising a table, a movable support adapted to receive successive layers of cigars from said table, a cigar box holding device comprising an abutment and a spring-pressed gripping member, a ribbon on said cigar support, said ribbon being adapted to receive cigars from their support and remove the same to the box held in the box holding device.

85 Signed at the city, county and State of 95 New York this 2nd day of September, 1920.

FRANCIS X. MALOCSAY.
